UNITED STATES PATENT OFFICE.

JAMES FOWLER HARKER, OF JOHANNESBURG, TRANSVAAL, SOUTH AFRICA.

BUFFER AND COUPLING FOR RAILWAY AND ROAD VEHICLES.

1,105,511.

Specification of Letters Patent.

Patented July 28, 1914.

Application filed March 13, 1913. Serial No. 754,004.

To all whom it may concern:

Be it known that I, JAMES FOWLER HARKER, a subject of the King of Great Britain, and resident of Johannesburg, Province of Transvaal, Union of South Africa, have invented certain new and useful Improvements in Buffers and Couplings for Railway and Road Vehicles, of which the following is a specification.

10 This invention relates to an automatic railway buffer-coupling.

Although primarily intended for use with railway vehicles it can also be used as a coupling for road vehicles.

15 The object of the invention is to construct a simple and efficient automatic buffer-coupling the employment of which will prevent the accidents to shunters which now frequently occur with existing couplings. It 20 completely obviates the necessity for the shunter to place his hands in a position which will expose him to danger during the coupling operation.

The invention will be fully described with 25 the aid of the accompanying drawings wherein—

Figure 1 shows my improved buffer-coupling in part sectional elevation. Fig. 2 is a plan of the same, and Fig. 3 is a front elevation.

In constructing my improved automatic buffer-coupling the buffer or head 1 is fashioned with a cavity 2 which—as shown in Figs. 1 and 2—is open at the top. A recess 3 is formed in the rear end of the buffer 1 communicating with the cavity 2 at the back thereof. The recess 3 is beveled or inclined at the top as indicated at 4 in Fig. 1 and it is rounded at the top as indicated at 5 in Fig. 2 to permit of the requisite movement within the cavity 2 and recess 3 of the coupling pin or member 6. The coupling pin 6 which as shown is of more or less hook shape is constructed at the rear end 45 with a square hole 7.

In the sides of the buffer 1 at the rear end there are provided two cylindrical holes 8, 9 which are placed opposite each other and communicate with the recess 3, the one 50 8 being somewhat larger in diameter than the other 9. In the holes 8, 9 there is arranged a bolt or pin 10 which is adapted to rotate therein. The bolt 10 is constructed with a square portion 11 which fits the 55 square hole 7 in the rear end of the coupling pin 6. This insures the movement of the

coupling pin 6 with the bolt when the latter is revolved in the holes 8, 9.

12, 13 are bosses formed on the outside of the buffer 1 around the outer ends of the holes 8, 9. The bolt 10 is at one end 60 fashioned with a head or enlargement 14 to which is attached the operating handle 15 which may be fixed or pivoted thereto.

16 is a nut which is screwed on to the other and threaded extremity of the bolt 10, and 65 17 is a split pin or the like for retaining the nut in position.

The coupling pin 6 is constructed with a projection 18 which is adapted to be engaged by a catch or trigger 19. The catch or trigger 19 is pivoted between two lugs 20, 21 which are formed on the inside of the buffer flange 1^a above the cavity 2; 22 being a split pin or the like which serves as 70 the pivot pin for the catch or trigger 19. The catch or trigger 19 is constructed with two projecting parts or arms 23, 24 which project downwardly into the cavity 2. To the ends of the arms 23, 24 there are attached the pins or pieces 25, 26. The pins or pieces 25, 26 are preferably attached to the ends of the arms 23, 24 by means of split pins or the like 27, 28. The pins 25, 26 project through holes 29, 30 in the front 75 of the buffer 1 and operate automatically upon contact of the buffers of two vehicles to cause the trigger 19 to disengage the coupling pin 6 and allow the latter to engage the coupling link 31 in the manner 80 shown. The catch or trigger 19 is preferably so constructed that the pins 25, 26 project through the holes 29, 30 as shown in Figs. 1 and 2 when said catch or trigger 85 is in its normal position as well as when it is supporting the coupling pin 6. The said catch or trigger is also so constructed that when the pins 25, 26 are pushed inward until their outer ends are in the holes 29, 30 the back of the catch at 32 in Fig. 1 90 comes into contact with the flange 1^a of the buffer between the lugs 20, 21 and serves as a stop for said catch. The pins 25, 26 are loosely attached (for example by the split pins 27, 28) to the arms 23, 24 so as to 95 prevent their sticking in the holes 29, 30 in the event of one of said pins only being struck by the buffer of the other vehicle which is to be coupled.

33 is an opening provided in the front of 110 the buffer which opening communicates with the cavity 2 and through which opening the

link 31 enters said cavity in order to be engaged by the coupling pin 6. This opening 33 as shown in Fig. 3 is preferably rounded at the tops of the sides as indicated at 34, 35 5 and it is preferably beveled outwardly at the bottom as indicated at 36 and to a slightly lesser extent at the sides and top. The bottom of the cavity 2 is preferably constructed to form a flat surface 2^a for the link 10 31 to rest upon when in position. The opening 33 is made of a sufficient size to allow for the maximum variation in the height of the buffers on different vehicles and the pins 25, 26 are so positioned that the contact of 15 buffers fixed at different levels will always insure disengagement of the catch or trigger 19 and the engagement of the coupling pin 6 with the link 31. By providing the two pins 25, 26 at opposite sides of the cavity 2 20 it will be evident that should the buffers come together with their faces at an angle to each other one or the other of the pins 25, 26 will be engaged and moved inward which will result in the disengagement of the coupling pin 6 and the coupling together of the 25 vehicles.

37 is a hole which is formed through the bottom of the buffer 1 into which hole the hooked end of the coupling pin 6 falls when 30 it engages the link 31. The hole 37 at the front is preferably hollowed as shown so that the front end of the pin 6 may pass freely from the hole 37, when turned from coupled to uncoupled position. However 35 the pin 10 engages the upper part of the hole 37 as indicated at 38 and this relieves the bolt 10 of a portion of the stress due to pull.

The operation of the buffer coupling is as 40 follows: The coupling pin 6 of the one buffer being in the position in which it is indicated by the dotted lines in Fig. 1 is retained in that position by the catch or trigger 19, the

pins 25, 26 then projecting beyond the face of the buffer as shown in the drawing. The 45 link 31 is in position in the buffer of the other vehicle that is to say it is in the position in which the link is shown in the drawing. As the vehicles approach the outer end 50 of the link 31 enters the cavity 2 in the opposite buffer through the opening 33 and when the buffers come into contact either or both of the pins 25, 26 are pushed inward which lifts the catch or trigger 19 and allows the coupling pin 6 to fall into engagement with the link. To uncouple the vehicles all that is necessary is to rotate the bolt or pin 10 by means of the handle 15 until the coupling pin 6 is engaged by the catch or trigger 19. The link 31 remaining engaged by the coupling pin in the other vehicle is drawn out of the buffer when the vehicles are separated.

What I claim as my invention and desire to protect by Letters Patent is:—

An automatic railway buffer-coupling comprising a coupling member pivotally supported within said buffer, a gravity catch pivoted to the buffer and adapted to engage the coupling member to retain it in its uncoupled position, means connected with said catch comprising a pair of arms which extend outwardly in opposite directions, and a pair of pins which project through holes in the front of the buffer and on opposite 75 sides thereof so that the catch is automatically released by the contact therewith of the opposite buffer.

In testimony whereof I have signed my name to this specification in the presence of 80 two subscribing witnesses.

JAMES FOWLER HARKER.
